FOREIGN PATENT DOCUMENTS

WO WO 2014/081812 5/2014

Primary Examiner — Cathron C Brooks*Assistant Examiner* — Samantha Q Lawrence(74) *Attorney, Agent, or Firm* — Knobbe Martens Olson
& Bear LLP(57) **CLAIM**

The ornamental design for a medical device handle, as shown and described.

DESCRIPTION

FIG. 1 is a front, top, and side perspective view of a medical device handle embodying our new design.

FIG. 2 is a left side view thereof.

FIG. 3 is a right side view thereof.

FIG. 4 is a front view thereof.

FIG. 5 is a back view thereof.

FIG. 6 is a top view thereof; and,

FIG. 7 is a bottom view thereof.

Broken lines are used to illustrate features of the medical device handle which form no part of the claimed design. Break lines are used to indicate that any portion of the medical device handle between the break lines forms no part of the claimed design.

1 Claim, 7 Drawing Sheets(56)
